DISPLAY STAND FOR SHOW WINDOWS

Elie François Hubert d'Horaene,
Brussels, BelgiumApplication May 29, 1945, Serial No. 596,536
In Belgium June 6, 1944

6 Claims. (Cl. 211—128)

1

My present invention relates to improvements in display stands made up with the aid of elements, preferably of hardened glass or of any other material (metal, Plexiglas, wood, etc.) for different articles, especially for show-window articles. It relates also to the pieces of furniture obtained with the aid of such a stand.

The object of the invention is to render possible to determine in a simple and automatic manner (that is to say without the window-dresser or display man having to perform any regulating work) the position in height or in depth of objects which are to be displayed.

According to the invention, this stand comprises a sheet, for instance a glass sheet, of big volume, which is placed upright and which possesses, at its upper part, some steps each of which may cooperate with a sheet of the same height as the step disposed at right angles with regard to the sheet and fitted into the latter, in a known manner, with the aid of slits having a width that is substantially equal to the thickness of the sheets, the steps and the sheets, placed at right angles to the latter, constituting cross-shaped supports for elements made habitually of glass, for instance plates bearing objects to be displayed.

On the annexed drawings:

Figure 1 illustrates the principle which forms the basis of the invention. This figure represents a stand with three steps; if desired, only two steps may be provided.

Figs. 2 and 3 show separately the elements which can enter into the formation of a stand according to the invention.

Figs. 4, 5, 6 and 7 show different stands based on the principle illustrated in Fig. 1.

The stand, making the subject matter of the invention, is composed in its simplest form, represented in Fig. 1, of a sheet, for instance a glass sheet 1 (big volume) which, when used, is placed upright and has in its upper part some steps 2, 3, 4 (Fig. 2).

With each step cooperates a sheet 5, 6 or 7 (Fig. 3), also of glass, which has the same height as the step, which is disposed at right angles with regard to the sheet 1, and which is assembled with this latter thanks to the fact that the sheet 1 has slits 8 which, proceeding from the lower part of each step, extend vertically half-way up of this step, whereas the sheets 5, 6 or 7 have notches 9 proceeding from one of the edges and extending vertically half-way up. The assemblage can also be carried out by providing in the sheet 1 notches 8 beginning above, but in this

2

case the position of the sheets 5, 6 and 7 must be reversed, and these sheets must be placed in such a way that the notches or slits begin at the lower edge, coming into contact with the ground and rise half-way up.

The notches 8 and 9 have a width which is equal to or slightly greater than the thickness of the sheets.

Thanks to the cooperation of the steps 2, 3, 4 and of the sheets 5, 6, 7 cross-shaped supports are being formed for plates 10 on which different objects, as shoes, neckties, etc., can be placed. In consequence, these objects can be displayed in this way on steps placed at intervals according to the depth and whose position as well as regards the height as the depth is determined automatically, that is to say without the window dresser or display man having to do any regulating work.

Fig. 4 represents a stand wherein use is made of a sheet 1a, formed by the juxtaposition in the lengthening of one by another of two sheets 1, so as to form on either side of a central support 11, a step 12 and a step 13, the steps 12 and the steps 13 being each on one and the same level.

In piece 1a, the slits are in the upper part, whereas in the sheets 5 and 6 and in the sheet 14, they are in the lower part.

Furthermore (Fig. 5), it is possible to combine an ensemble such as represented in Fig. 4 with an ensemble such as represented in Fig. 1, the sheet 1 being fitted into the central support 14 of sheet 1a; sheet 1 is placed at right angles with respect to sheet 1a.

Fig. 6 shows a stand formed by the fitting into each other of two ensembles of the type represented in Fig. 1, the sheets 1 being placed in directions perpendicular one with regard to the other.

Fig. 7 relates to a disposition wherein sheets 1, placed in directions parallel one with respect to the other, are furnished each with sheets 5, 6, 7 of the type represented in Fig. 1.

The steps 2, 3 and 4 of each piece of furniture are united by sheets 15, which are placed horizontally and rest on cross-shaped supports formed by each sheet.

The described stands are of course applicable not only to displays but also in a general way to furniture and to the different domains of decorative art.

They have of course been given only by way of example and numerous modifications can be conceived without departing from the spirit and scope of the invention.

What I claim is:

1. A display stand comprising a main panel disposed on edge and provided at its top with steps formed with horizontal rectilinear edges situated at increasing heights and a series of transverse panels having each one upper horizontal edge and placed at right angles with respect to the main panel, each transverse panel corresponding to one step of the main panel and having the same height as the said step so that each step and the corresponding transverse panel form a cross-shaped support for an element to carry objects adapted to be displayed, the assembly between the main panel and the transverse panels being obtained by means of slits in the main panel having a width substantially equal to the thickness of the transverse panels, and a slit in each transverse panel having a width substantially equal to the thickness of the main panel.

2. A display stand comprising a main panel disposed on edge and provided at the top with steps formed with horizontal rectilinear edges and a series of rectangular transverse panels placed at right angles with respect to the main panel, each transverse panel corresponding to one step of the main panel and having the same height as the said step so that each step and the corresponding transverse panel form a cross-shaped support for an element to carry objects adapted to be displayed, the assembly between the main panel and the transverse panels being obtained by means of slits formed in the main panel and having a width which is substantially equal to the thickness of the transverse panels, and a slit in each transverse panel having a width substantially equal to the thickness of the main panel.

3. A display stand comprising a main slab disposed on edge and stepped at its top so as to form steps of increasing height, and transverse slabs placed crosswise of said steps and having heights corresponding, respectively, to the heights of the steps, the said second slabs being slotted for crosswise engagement with the main slab in upright position, each step being provided with a transverse slab and forming with the latter a cross-shaped support for an element to carry objects adapted to be displayed.

4. A display stand comprising a main panel disposed on edge and provided at its top with steps formed with horizontal rectilinear edges situated at increasing height to constitute two symmetrical flights of steps rising to the axis of symmetry of said main panel, and a series of transverse panels having each one upper rectilinear edge and placed at right angles with respect to the main panel, each transverse panel corresponding to one step of said main panel and having the same height as the said step so that each step and the corresponding transverse panel form a cross-shaped support for an element to carry objects adapted to be displayed, the assembly between said main panel and said transverse panels being obtained by means of slits formed in the main panel and having a width which is substantially equal to the thickness of the transverse panels, and a slit in each transverse panel having a width substantially equal to the thickness of the main panel.

5. A display stand comprising a first main panel disposed on edge and provided at its top with steps formed with horizontal rectilinear edges situated at increasing height to constitute two symmetrical flights of steps rising to the axis of symmetry of said first main panel, a first series of transverse panels having each one upper rectilinear edge and placed at right angles with respect to said first main panel, each transverse panel of said first series corresponding to one step of said first main panel and having the same height as the said step so that each step of the main panel and the corresponding transverse panel form a cross-shaped support for an element to carry objects adapted to be displayed, a second stepped main panel engaged in a slot provided along the axis of symmetry of said first main panel at right angles to said first main panel and a second series of transverse panels interengaged with the steps of said second main panel and forming therewith cross-shaped supports for elements to carry objects adapted to be displayed, the assembly between each main panel and the associated transverse panels being obtained by means of slits formed in said main panels and having a width which is substantially equal to the thickness of the transverse panels and slits in each of said transverse panels having a width which is substantially equal to the thickness of said main panels.

6. A display stand comprising a first main slab disposed on edge and provided at its top with steps of increasing height, a second main slab also disposed on edge and provided with steps of increasing height, the said main slabs being placed at right angles to each other and fitted together at their higher ends by means of interengaging slots, rectangular transverse slabs placed crosswise to each of the main slabs and corresponding each to one step of one of the main slabs and having the same height as such step and forming with the latter cross-shaped supports for elements to carry objects adapted to be displayed, the assembly between each main slab and the associated transverse slabs being obtained by means of slits formed in the main slabs each having a width which is substantially equal to the thickness of the transverse slabs, and slits in each transverse slab having a width which is substantially equal to the thickness of the main slabs.
